EXHAUST DEFLECTOR

Linus E. Russell, Springfield, Ohio

Application February 8, 1954, Serial No. 28,915

Term of patent 14 years

(Cl. D14—6)

FIG 1.

FIG 4.

FIG 2.

FIG 3.

To all whom it may concern:

Be it known that I, Linus E. Russell, a citizen of the United States, residing at Springfield, Clark County, Ohio, have invented a new, original, and ornamental Design for an Exhaust Deflector, of which the following is a specification, reference being had to the accompanying drawing, forming a part thereof, in which

Fig. 1 is a perspective view of an exhaust deflector embodying my design;

Fig. 2 is a bottom view;

Fig. 3 is a side view thereof; and

Fig. 4 is an end view thereof.

I claim:

The ornamental design for an exhaust deflector, substantially as shown.
